United States Patent Office.

EDWARD M. TROTH, OF NEW YORK, N. Y.

Letters Patent No. 66,422, dated July 2, 1867.

IMPROVED ROCK-DRILLING MACHINE.

The Schedule referred to in these Letters Patent and making part of the same.

TO ALL WHOM IT MAY CONCERN:

Be it known that I, EDWARD M. TROTH, of the city, county, and State of New York, have invented certain new and useful improvements on Rock-Drilling Machines, of which the following is a full, clear, and exact description, reference being had to the accompanying drawings, forming part of this specification, and in which—

Figure 1 represents a rock-drilling machine, as arranged for tunnelling purposes, constructed according to my improvement.

Figure 2, a longitudinal vertical section of the same, with the drills or cutters removed.

Figure 3, a face view of a combined ram and drill-head or holder.

Figure 4, a rear view of the frame or back end portion thereof.

Figure 5, a front view of the same; and

Figure 6, a view of one of the locking eccentrics for holding and adjusting the machine in the tunnel.

Similar letters of reference indicate corresponding parts.

The nature of my invention consists, firstly, in a novel combination, in the one machine, of independent engines for drilling and ramming or splitting the rock by or through a combined drill-holer and ram; also in a certain combination of sliding-box, rotating-tube and ram or drill-holder, and of cushions to reduce jar and prevent injury; likewise, in connection with said tube, of an operating-wheel to the latter, and attachment, capable of being uncoupled, with the piston-rod of the ram-driving engine; and, furthermore, in a novel combination of mechanism or gear for establishing at pleasure either the feed of the drills, their picking action, or throw of the ram; and lastly, in an arrangement or application to the frame of the machine of eccentric bearing-wheels or rollers, for adjusting and holding the machine to its work.

Referring to the accompanying drawing, A represents the front and B the back end frames or portions of the main frame, of spider form or construction, C the connecting sides or beams, and D longitudinal tie-rods or braces uniting the end portions or frames A B. Carried by the rear portion or frame B are two steam-cylinders E F, provided with valve-boxes G H, containing ordinary or any suitable valves for controlling the motion of reciprocating pistons within said cylinders, of different strokes, the centrally arranged cylinder E having a piston of comparatively long stroke, while the latterly arranged cylinder F has a piston of comparatively short stroke. These two arrangements form what may be termed separate engines, the shorter-stroked one serving to work the drills or cutters, while the longer-stroked engine answers to drive the ram, and it may be to adjust or feed the machine along the tunnel. I is the piston-rod of this central or ramming cylinder. This rod may be made hollow, and is arranged to fit within a cylindrical sleeve or tube J, with which it may be geared by a detachable coupling, a, so as to reciprocate said tube, the rod fitting against a shoulder, b, of the tube when propelling it forward to ram. This gear of the rod I and tube J should be such as to admit of the rotation of said tube, which is provided with a longitudinal slot or groove, c, to allow of its sliding through yet rotating in connection with a worm-wheel, K, by means of a feather in or to said wheel. The wheel K is restrained from movement along with or in direction of the length of the tube J, by its being hung to turn within a fixed bearing formed on or in a cross-brace, d, uniting the side beams C of the frame. This tube J, after passing through the wheel K, is extended frontwards so as to project within and through, in a lengthwise direction, a longitudinally sliding box, L, of a square or other form, that will restrain it from turning in the front end frame A through which it passes, said sliding-box running on or being supported by rollers e e, to facilitate its travel. In the ends of this box are bearings f f, for the tube J to rotate in, but which tube is restrained by means of suitable end collars from longitudinal play therein, or otherwise than in conjunction with the box L, excepting such as is provided for by rubber or other cushions h h, at or near opposite ends of the box. Attached to the tube J, at its forward end, is the drill-holder and ram M, of suitable form and size relatively to the frame to establish clearance and afford other requisite facilities, such holder not merely carrying the drills i, arranged to project from it in front, as desired, to effect the cut or cuts, but also being provided or studded with ramming blocks J, for, after the drills have done their work, action on wedges inserted in the cuts to, by using the holder M as a ram, split and detach the cut rock. This ramming action is produced by the piston of the cylinder acting through the rod I, coupling a, tube J, and sliding-box L, the cushions h h, both

ramming action of the holder M and picking stroke of the drills, as hereinafter explained, serving, by arrangement at opposite ends of the driving junction of the tube J and box L, to much more effectually jar, and prevent the injurious effects of concussion than does a spring or cushion at one end only. For the rock, the coupling α may be detached to prevent unnecessary working of the ramming engine, the rod I of which will then remain stationary and simply serve as a guide, or may do so, to the tube J. The rotation of the drill-holder M and picking action of the drills is or are effected by the engine, of which the cylinder, the piston-rod k of which gives, through a pitman, l, rotary motion to a crank, m, of a shaft, carrying a pinion, o, gearing into a wheel, p, hung on a shaft, q, which carries a screw, N, that in rotating the worm-wheel K. This gives a rotary motion, by the feathered gear of the wheel K with it, to the J, and consequently to the drill-holder M, with its drills i, which action may be exclusively used where only is needed. To give, however, to the drills their reciprocating or picking stroke, in addition to their ring one with the holder M, the following means are or may be resorted to: On the engine shaft n is a reel that carries an eccentrically arranged slide, adjustable by screws r, to vary the throw, and which, in itself, serves, through a pitman, O, to give motion to a rocking-lever, P, hung on a cross-shaft, s, supported in side beams C of the frame. This cross-shaft carries arms or levers t, connected at their outer ends by u to a free frame or clutch-box, Q, to which they are pivoted as at v, said frame locking when down, or in position represented for it in figs. 1 and 2, with a screw-box, R, which fits a groove w in the sliding-box L, as passing through or gearing with it a screw, S, carried by said sliding-box. By this means, it will be given, is a reciprocating or picking stroke given to the drills as they are rotated by the holder M. To do the same its or their feeding-stroke, to give to the cut in the rock its necessary depth before applying wedges and ram, the revolving-tube J is geared by wheels and pinions x y z z' with the screw S, which, in ing within the screw-box R, draws along with it the sliding-box L and tube J, with the drill-holder and its s. To run back the drills, supposing the tube J to be disconnected from the ram operating piston-rod I, by detachment as described of the coupling α , the pinion z may be unshipped and the screw S and drills run by rotating the screw in a reverse direction through, it may be, a pinion, b', operated by any suitable means. When it is required to apply the ram, the coupling α is re-established, drilling engine stopped, drills removed, clutch-box Q thrown up or back out of gear with the screw-box R, which, with the screw S, sliding-frame and tube J, are then free to move in a straight line or lines by the forward stroke of the piston-rod I, to the requisite quick and powerful stroke, under the influence of the ramming engine, to the holder or ram and ramming blocks j to act upon the wedges to split and break the cut or drilled rock, a number of such ramming strokes being given in quick succession. Though the drilling and ramming powers are thus, as it were, inct, and under the control of independent valves, they are in a measure connected for separate action, in varied ways described on the same device, drill-holder, or ram M, for performance of the work, and both ers may derive their supply of steam, air, or other propelling agent from a boiler or reservoir in the rear mon to both. The valve of the ramming engine may be regulated by hand to adjust the blow or ramming ke, while the valve of the drilling engine may be operated automatically by an eccentric, c', on the engine-shaft ad eccentric rod d', the force or throw of the picking stroke of the drills being, as before observed, regul'd by an adjustable eccentric driving-slide on the wheel Y. By means of the coupling α and clutch-box or ne Q, not only are the several motions previously described produced, without interference the one with the er, but the independence of the drilling and ramming powers fully secured, and the dragging of dead weight ided, as in the case of detaching the coupling α , whereby the ramming piston is allowed to remain stationary ing the picking and rotating actions of the drills. To adjust the machine to its proper position, and hold it a or steady in the tunnel for the performance of its work, the lower arms or legs of the spider-frames A and are provided with roughened or milled-edged eccentrics or rollers V, hung on eccentric bearings, and operated rods or handles e'. By these eccentrics V and wedges, applied between the rock and outer ends of the upper ns or legs of said frames A B, may the machine not only be readily adjusted and securely held for drilling ramming, but every facility afforded, by merely slackening the eccentrics and removing the wedges, to move whole machine bodily forward in the tunnel, to follow up the work, and which may be done by wedging, at edges, the holder or ram M in or against the rock and applying steam, supposing such to be the propelling ent, to the cylinder E or piston therein.

What I claim as my invention, and desire to secure by Letters Patent, is—

1. The combination, in the one machine, of separate engines for independent action of a combined drill-holder and ram, substantially as specified.

2. The combination of the sliding-box L, rotating tube J, and ram or drill-holder M, for operation together, herein set forth.

3. The cushions h , when applied at or near opposite ends of the sliding-box L , substantially as specified.

4. The combination of the wheel K, tube J, and piston-rod I, provided with a stopper together, as herein set forth.

5. The combination, with the sliding-box L , of the screw S , screw box T , and the equivalent gear, whereby the feed of the drills is established, a short picking action given to the same, or distinct ramming stroke or action produced, essentially as specified.

6. The application to the frames A and B of the eccentrics v , substantially as and for the purpose described. EDWARD M. TROTH.
